CARTRIDGE PRIMER SEATING TOOL

Richard J. Lee, Rte. 2, Hartford, Wis. 53027

Filed Jan. 26, 1970, Ser. No. 21,073

Term of patent 14 years

Int. Cl. D8—02

U.S. Cl. D8—14

Fig. 1

Fig. 2

Fig. 3

Fig. 4

Fig. 5

Fig. 6

FIG. 1 is a side elevational view of one side of a cartridge primer seating tool showing my new design;

FIG. 2 is a front elevational view thereof;

FIG. 3 is a side elevational view of the tool showing the side opposite that illustrated in FIG. 1;

FIG. 4 is a rear elevational view of said tool;

FIG. 5 is a top plan view of said tool; and

FIG. 6 is a bottom plan view of said cartridge primer seating tool.

I claim:

The ornamental design for a cartridge primer seating tool, as shown.
